[57] CLAIM

The ornamental design for a boot jack, as shown and described.

DESCRIPTION

FIG. 1 is a top plan view of a boot jack showing my new design;

FIG. 2 is a bottom plan view thereof;

FIG. 3 is a side elevational view thereof in the in-use position;

FIG. 4 is a front elevational view of FIG. 3;

FIG. 5 is an opposite side elevational view thereof. The rear end opposite the U-shaped yoke is substantially plain.
